DRAFT RIGGING

Donald S. Barrows, Rochester, N. Y., assignor to
The Symington-Gould Corporation, Rochester,
N. Y., a corporation of Maryland

Application February 14, 1934, Serial No. 711,247

13 Claims. (Cl. 213—30)

This application is a continuation in part of my application Serial No. 391,595 filed September 10, 1929, for Draft rigging.

This invention relates to railway draft rigging and the combination with such rigging of friction shock absorbing mechanism and, more particularly, to a form of shock absorbing or cushioning mechanism which is double-ended and contains cushioning means in each end, the center or intermediate portion of the casing being adapted for connection to associated draft sills or cheek plates thereon, whereby a greater amount of cushioning capacity may be made available under the action of buffing forces than under the action of draft forces.

The principal object of my invention, generally considered, is to provide a friction draft gear or cushioning mechanism comprising a housing receiving laterally movable friction blocks with a wedge block fitting therebetween, and resilient means disposed between said friction blocks and the sides of said housing for urging said friction blocks into engagement with said wedge blocks, means being desirably provided for holding the elements assembled with the housing, even when detached from associated draft rigging.

An object of my invention is the provision of a double-end draft gear or cushioning mechanism adapted for series application to provide a greater buffing than draft energy absorbing capacity, with the housing thereof slotted for receiving a draft key or other means for connection with associated sills.

Another object of my invention is the provision of shock absorbing mechanism comprising a casting or housing with one or more pockets, each of which contains friction shoes or elements, between which is disposed a central wedge for urging said friction elements apart, the friction members being retained in engagement by preferably curved plate springs disposed between the outer elements and the adjacent walls of the housing.

A further object of my invention is the provision of cushioning mechanism enclosed in a housing with top, bottom and side walls and intermediate transverse walls which divide the housing into compartments and on which associated wedges are adapted to move for increasing the frictional capacity.

A still further object of my invention is to provide cushioning mechanism involving a casing or housing enclosing cooperating friction wedges and an associated follower or followers held in place by lugs on the outer ends of the housing,

or, as an alternative, by a key extending through slots in opposite walls of the housing and one of the associated wedges.

Other objects and advantages of the invention relating to the particular arrangement and construction of the various parts will become apparent as the description proceeds.

Referring to the drawings illustrating my invention, the scope whereof is defined by the appended claims:

Figure 1 is a partial side elevational and partial vertical longitudinal sectional view of one embodiment of my cushioning mechanism.

Figure 2 is a partial and elevational and partial transverse sectional view on the line 2—2 of Figure 1, looking in the direction of the arrows.

Figure 3 is a view corresponding to Figure 1, but showing a modification.

Figure 4 is a fragmentary horizontal sectional view on the line 4—4 of Figure 3, looking in the direction of the arrows.

Figure 5 is a partial side elevational view and partial longitudinal sectional view of another embodiment of my invention, the mechanism in the left-hand end of the housing being shown in normal or free position, with that in the right-hand end of the housing being illustrated in compressed or closed position.

Figure 6 is a transverse sectional view on the line 6—6 of Figure 5, looking in the direction of the arrows.

Figure 7 is a transverse sectional view on the line 7—7 of Figure 5, looking in the direction of the arrows.

Figure 8 is a detail perspective view of one of the self-locking retainers for the resilient mechanism.

Figure 9 is a partial side elevational and partial vertical longitudinal sectional view of a further embodiment of my invention.

Figure 10 is a transverse sectional view on the line 10—10 of Figure 9, looking in the direction of the arrows.

Figure 11 is a view corresponding to Figure 9, but showing another modification.

Figure 12 is a partial end elevation and partial transverse sectional view on the line 12—12 of Figure 11, looking in the direction of the arrows.

Figure 13 is a view corresponding to Figure 11, but showing a further modification.

Figure 14 is a transverse sectional view on the line 14—14 of Figure 13, looking in the direction of the arrows.

Figure 15 is a view corresponding to Figure 13, but showing an additional modification.

Figure 16 is a transverse sectional view on the line 16—16 of Figure 15, looking in the direction of the arrows.

Referring to the drawings in detail, like parts being designated by like reference characters, and first considering the embodiment of my invention illustrated in Figures 1 and 2, a form of double end, series friction draft gear 1 is illustrated involving a housing or casing 2 formed by side or longitudinal walls 3, 4 and 5, the walls 3 being preferably the normally vertical walls and the walls 4 and 5 being respectively the top and bottom walls, although it will be understood that I do not wish to be limited to using the gear in this position. The walls 3, 4 and 5 are connected and braced transversely by transverse walls 6 preferably extending from the ends of a horizontal connecting web 7. Said web 7 and the corresponding portions of the side walls 3 are provided with a longitudinal slot 8 for receiving a draft key 9 or other means for connecting the housing and cushioning mechanism to associated draft sills or cheek plates thereon (not shown). In the present embodiment I have shown the cushioning mechanism associated with a horizontal yoke 10, the arms of which are correspondingly slotted to receive the key 9, the rearmost portion of said yoke preferably engaging the rear follower 12 locked in position by lugs 13 on the ends of the walls 4 and 5 which extend toward one another and overlie the upper and lower edges of said follower. The rear end of the housing 2 may be made without lugs 13 to suit a standard rear follower or filler, which may then be used instead of the rear follower 12. The front follower 12 is preferably locked in position by similar lugs 13 on the front of the housing.

The cushioning means in the housing 2 involves two sets of associated wedges or shoes and resilient means, one set disposed forwardly of the front partition 6 and the other disposed rearwardly of the rear partition 6. Between the two partitions 6 the housing is preferably cored, as illustrated, to lighten the weight thereof. The pockets or compartments 14 forwardly and rearwardly of the front and rear partitions 6 are preferably defined at their outer ends by flanges or webs 15 partially closing the openings into the housing and preferably extending from the extreme edges of the side walls 3. These flanges provide upper and lower pockets 16 in the main compartments 14 receiving upper and lower resilient means 17 which preferably take the form of sets of curved plate springs. Associated with each set of springs is a friction shoe or wedge member 18 formed with double friction surfaces 19 providing a shoulder 20 at the junction of said surfaces, and normally disposed between said friction elements is a double wedge member 21, formed like the friction elements 18 with double friction surfaces 22 engaging the friction surfaces 19 on the friction elements 18 and having shoulders 23 cooperating with the shoulders 20 on the friction elements 18 to interlock the members together. The outer or large end of each wedge member 21 is normally engaged by the corresponding follower 12, and the outward relative movement of said member 21 thereby limited, and the outer surface of the front follower 12 may be engaged by the butt or stem of an associated coupler 24.

The operation of my cushioning mechanism 1 may be as follows when the coupler stem 24 is connected to the yoke 10 in any usual or desired

manner and the yoke slots 25 and corresponding slots in the cheek plates or draft sills (not shown) are extended rearwardly beyond the normal position of the slot 8 so that under the action of buffing forces the housing 2 is allowed to move rearwardly, while under the action of draft forces it is retained immovable or substantially so with respect to the associated sills. When draft forces are applied to the coupler, the yoke 10 is pulled forwardly moving the rear follower 12 into the housing and pushing the associated friction element or wedge 21 between the shoes or friction devices 18 and separating them against the resistance of the springs 17, thereby actuating the cushioning mechanism in the rear pocket 14 only, on account of the housing 2 being held stationary by the key 9, and utilizing only one half of the total capacity of the double end gear and permitting the coupler to travel only one half of the total permissible compression of the gear. Upon full compression, it will be seen that the movement of the follower is arrested by engagement with the flanges, shelves or partial transverse diaphragms 15 and also by the walls 3 of the housing which serve as limiting means and prevent the springs from being pressed flat, thereby protecting them against overloads.

Under the action of buffing forces, however, the coupler stem 24 engages the front follower 12 pushing the front double wedge rearwardly and at the same time moving the housing rearwardly over the rear friction elements, on account of the rearward elongation of the slots 25, it being understood that the rear portion of the yoke or rear follower is associated with a backstop or other limiting means (not shown) for effecting compression of the mechanism. It will, therefore, be seen that a full compression of the gear at both ends thereof is permitted on buff, thereby providing for not only an increased buffing capacity, but for a coupler travel equal to the sum of the travel permitted by the friction elements at each end of the gear. Although for convenience and economy in manufacture the gear is preferably made symmetrical so that the travel and capacity provided by each end is identical, yet this is not essential as the capacities and travels of the two ends of the gear may be equal or different as desired.

Although I have described a preferred manner of using my double end gear, it is to be understood that, if desired, it may be utilized so that the total capacity is used under both buff and draft and it may also be employed so that the present side walls are disposed as top and bottom walls, that is, the gear may be rotated 90° about a longitudinal axis.

Referring now to the embodiment of my invention illustrated in Figures 3 and 4, a gear 1^a is there disclosed having a housing 2^a provided with partitions 6^a and a slotted web 7^a, as in the previous embodiment. The partitions 6^a provide compartments 14^a at each end of the housing, the outer ends of said compartments being partially closed by flanges 15^a, leaving, however, openings 26 for receiving the resilient means 17^a, the friction shoes 18^a and the double wedge member 21^a. In the present embodiment, the wedge member and shoes are formed with double cooperating friction surfaces and shoulders causing interlocking between the parts, the outer or large end of the double wedge member 21^a being preferably integral with the follower portion 12^a rather than separate therefrom as in the first embodiment. Instead of providing 75

lugs on the housing to limit outward movement of the follower 12^a, such movement is limited in the present embodiment by forming a slot 27 in the double wedge portion 21^a and slots 28 in the side walls 3^a of the housing 2^a, a key 29, interlocked by engagement between a lug 30 on the wedge 21^a and a slot 31 in said key, being received in said slots 27 and 28 to limit outward movement of the double wedge 21^a with respect to the housing. The necessary inward movement of the wedge 21^a with respect to the housing is permitted by the outward elongation of the slot 27, and limited by engagement between the follower 12^a and the flanges 15^a. Although the mechanism in only one end of the housing is illustrated, it will be understood that corresponding mechanism may be used in the other end and that the mechanism, except as specifically described in connection with the present embodiment, desirably corresponds with that of the first embodiment and may be used in the same way.

Referring now to the embodiment of my invention illustrated in Figures 5 to 8, inclusive, a cushioning mechanism or draft gear 1^b is there disclosed having a housing or casing 2^b formed by side or longitudinal walls 3^b, 4^b and 5^b, the walls 3^b being preferably the normally vertical walls and the walls 4^b and 5^b being respectively the top and bottom walls, although it will be understood that I am not limited to using the gear in this position. The walls 3^b, 4^b and 5^b are connected and braced transversely by walls 6^b preferably extending from the ends of horizontal connecting webs or flanges 7^b. Said webs or flanges 7^b and the corresponding portions of the side walls 3^b are provided with longitudinal slots 8^b for receiving a draft key (not shown), or other means for connecting the housing and cushioning mechanism to associated draft sills or cheek plates (not shown). In addition to the web portions 7^b, the transverse walls 6^b are desirably braced by longitudinally extending webs 33. The mechanism 1^b may be associated with a horizontal yoke, as in the embodiment of Figures 1 and 2, although I do not wish to be limited to this.

The cushioning means or draft gear 1^b involves two sets of associated wedges or shoes and resilient means, one set disposed forwardly of the front partition 6^b and the other disposed rearwardly of the rear partition 6^b. Between the two partitions and outwardly thereof, the walls of the housing, as well as said partitions, are desirably apertured, as indicated at 34, 35 and 36, to facilitate core removal and assembly of the parts. The housing is provided with a compartment or pocket 14^b in each end, the forward compartment being disposed forward of the front partition 6^b and the rear compartment being disposed rearward of the rear partition 6^b. Said compartments are desirably defined at their outer edges by flanges or webs 15^b partially closing openings into said compartments and preferably extending from the extreme edges of the side walls 4^b and 5^b adjoining the corresponding portions of the walls 3^b. These flanges 15^b provide upper and lower pockets 16^b, in the main compartments 14^b, receiving upper and lower resilient means 17^b which desirably take the form of sets of curved plate springs. Associated with each set of springs is a wear plate 37, the end portions of which are desirably notched, as indicated at 38, to receive corresponding nibs 39 which cause the individual plates to be inter-

locked with respect to one another and said wear plate, thereby preventing undesired lateral shifting therebetween, in a manner such as described and claimed in the Suckow Patent No. 1,884,913 of October 25, 1932.

Associated with each set of springs is a friction shoe or wedge member 18^b formed with a friction surface 19^b engaging a corresponding friction surface 22^b on a center wedge or spreader member 21^b. As in previous embodiments, lead inserts 32^b or other means for making the frictional action uniform, are employed. Each central wedge member 21^b desirably has an outer portion 12^b extended laterally to function as a follower for engagement with a drawbar or yoke, 15 as the case may be, and is guided in its longitudinal movement by the adjacent portions of the webs 15^b.

In order to facilitate release of the mechanism, as well as increase the capacity of the gear, the center wedges or plungers 21^b and the associated friction shoes or wedges 18^b are formed hollow or provided with pockets receiving release springs 40, which take the form of relatively long coils in the present embodiment. Said release springs 25 act at their inner ends on the transverse partitions 6^b and are centered about projections or lugs 41 outstanding therefrom. The outer ends of said springs act on annular flange portions 41' of the follower portions 12^b of the center 30 wedges 21^b. Because of said release springs, it is not necessary to make the wedges blunt enough to be self-releasing, as in the embodiments of Figs. 1 to 4, inclusive.

In order to provide renewable wearing surfaces 35 on the transverse partitions 6^b, friction plates 42 are desirably applied over the outer surfaces of said partitions for engagement by the wedges 18^b and the adjacent ends of the curved plate springs 17^b. In order to prevent contraflexure, and an undesired amount of bending of the curved plate springs when the gear is compressed, as shown at the right-hand side of Figure 5, the spring-engaging surfaces 43 of the wedges 12^b are desirably formed slightly concave cylindrically to 45 enlarge the bearing areas and provide surfaces which correspond generally with the normal curvature of the springs when compressed.

In order to hold the parts of the mechanism assembled, bolts 44 are provided extending through 50 apertures 45 in the partitions 6^b and with their heads 46 received in corresponding pockets 47 which normally prevent rotation thereof. The outer ends of the bolts pass through apertures 48 in retainers 49, into pocket portions 50 in said 55 retainers which function each as a socket wrench for tightening the associated nut 51. Said retainers are made self-locking by having the heads or outer end portions 52 non-circular, as shown most clearly in Figure 8, and normally nesting in 60 corresponding portions in the center wedges 21^b. Washers 53 of lead, wood, or other material which is readily disintegrated or destroyed, are desirably initially employed with the nuts 51, so that the gear may have an initial released length 65 slightly shorter than the normal released length, to facilitate initial application of the gear, said washers being disintegrated or destroyed and eliminated in service, allowing the gear to assume the desired normal length.

In order to allow for application and removal of the bolts 44, the apertures 45 in the walls 6^b are each flared at one side toward one of the walls 4^b and 5^b, as indicated at 54, thereby allowing application or removal of the bolts, upon canting to 75

diagonal positions, through the apertures 36 in the partitions and center wedge openings, when enough of the normally enclosed material has been removed.

5 The use and operation of the gear illustrated in Figures 5 to 8, inclusive, may correspond with that of Figures 1 and 2.

Referring now to the embodiment of my invention illustrated in Figures 9 and 10, a gear 1^c is illustrated which is single-ended rather than double-ended, and corresponds somewhat with the gear of Figures 5 to 8, inclusive, turned end for end with the key slots 8^c in the plunger or central wedge portion 21^c instead of in the housing portion, the head of said plunger portion 21^c being enlarged to fill the draft gear pocket and formed with abutment portions 49^c for outside relatively long release springs 40^c. Otherwise, the gear may correspond substantially with that of Figures 5 to 8, inclusive, having, however, only one friction wedge and curved plate spring pocket 14^c, comprising two parts or compartments 16^c, each receiving a wear plate 37^c engaged by a nest of curved plate springs 17^c, in turn acted on by a wedge or friction shoe 18^c. Some, or all, of the engaging friction surfaces of the central wedge portion 21^c and the lateral wedges 18^c may be provided with lead inserts 32^c, as in previous embodiments. In order to provide a renewable wearing surface on the transverse or end wall portion 6^c of the housing 2^c, a friction plate 42^c is desirably applied over the inner surface of said wall 6^c for engagement by the adjacent portions of the wedges 18^c and the curved plate springs 17^c.

40 In order to hold the slotted plunger member 21^c assembled with the housing 2^c, bolts 44^c may be employed extending through adjacent flanges of said members. As in the previous embodiment, a lead or destructible washer 53^c may be employed with each bolt to hold the parts initially closer together to normally facilitate assembly, while allowing said parts to assume normal positions after the gear has been put into service. Cotter 45 or other means 55, for keeping the nuts 51^c in the desired position on the bolts 44^c, are employed, said nuts 51^c being illustrated as of the "castle" type. The release springs 40^c act between the flange portions 49^c on the slotted plunger member 21^c and flanges 15^c on the housing 2^c, which latter flanges restrict the opening to the pocket 14^c, and their inner edge portions serve to guide the slotted plunger 21^c.

50 Although the gear illustrated in Figures 9 and 10 is of the single-ended type, it may be made double-ended like the gear of Figures 5 to 8, inclusive, by making that portion to the left of the transverse central plane 56 symmetrical with that to the right of said plane, as shown in Figure 9. It will also be understood that the gear may be shortened considerably as by eliminating the release springs 40^c and decreasing the length of the plunger or wedge-shaped portion 21^c which spreads the wedges or shoes 18^c, thereby forming what may be considered as a combined short draft gear and follower block, the wedging angles or inclination of the friction surfaces where the center wedge 21^c engages the side wedges 18^c being made self-releasing, or the inclination thereof increased, to correspond with that of the friction surfaces in the embodiments of Figures 1 to 4, inclusive. If such is done, the wedge-shaped portion 21^c and the associated wedges 18^c may be formed with interlocking shoulders, as shown, for 75 example, in Figure 3. In this case it may also be

found desirable to form wall portions 4^c and 5^c integral with the slotted portion rather than the portion which houses the wedge blocks 18^c, said nests of curved plate springs 17^c being then concave inwardly with their convex sides slidable in operation on the walls 4^c and 5^c, as will be understood. A plane follower, as shown at 12 in Figure 1, and normally engaging the blunt ends of the wedges 18^c would then take the place of the wall 6^c, the other ends of the springs 17^c being prevented from slipping off the sharp ends of the wedges 18^c by means of flanges on said wedges overlying the ends of said springs. As a further modification, the blunt ends of the wedges may, if desired, be provided with spring-locating flanges 15 to correspond with those at the sharp ends.

55 Referring now to the embodiment of my invention illustrated in Figures 11 and 12, a gear 1^d is shown which corresponds with the gear 1^b of Figures 5 to 8, inclusive, except that it is single-ended like the gear 1^c of Figures 9 and 10, and the central wedge 21^d is unprovided with a follower portion and adapted for use with a follower 12^d. The housing 2^d is provided with slots 8^d and 57, so that it may be connected with associated cheek plates and/or draft sills (not shown) by means of a draft key (not shown) extending transversely therethrough either way, thereby adapting said gear to be used with its long lateral dimension disposed either vertically or horizontally. As in the previous embodiment, the gear may be converted into one of the double-ended type by making the parts thereof to the right of the transverse central plane 56^d symmetrical with those to the left of said plane.

60 In the present embodiment, the pocket 14^d receives curved plate springs 17^d, an associated wear plate 37^d, a friction plate 42^d, and friction wedges 18^d, as in the embodiments of Figures 5 to 10, inclusive. In addition, the friction wedges 18^d may have associated therewith an auxiliary friction member 58 forming an abutment for the release springs 40^d which act between it and an interior wall portion 59 of the central wedge 21^d, said auxiliary friction member being pressed into engagement with the inner webs 60 of the friction shoes 18^d, thereby serving to generate additional friction upon lateral movement of said shoes, as will be understood. As in the preceding embodiment, a bolt 44^d serves to retain the parts of the mechanism in assembled relation and a lead or destructible washer 53^d may be associated therewith, as previously mentioned.

65 Referring now to the embodiment of my invention illustrated in Figures 13 and 14, a gear 1^e is illustrated which may correspond with the gear 1^d of the preceding embodiment, except that larger internal release spring means 40^e are employed, and the auxiliary friction member 58 is omitted. In order to provide for such larger release springs, the transverse partition wall 6^e is desirably inwardly embossed, as indicated at 61, to provide abutments for the outer of the release spring means, said embossed portion having an outwardly extending annular projection 62 which serves for centering said outer release spring 40^e and as an abutment for the inner release spring 63. As in preceding embodiments, a bolt 44^e may be employed to hold the parts in assembled relation, as will be understood. It will also be understood that the gear, although shown as single-ended, may be converted into a double-ended gear by making the parts to the right of the transverse central plane 56^e correspond with those to the left of said plane, as shown in 75

Figure 13. Except as specifically disclosed, the gear of Figures 13 and 14 may correspond with that of Figures 11 and 12.

Referring now to the embodiment of my invention illustrated in Figures 15 and 16, a gear 1^g is illustrated which corresponds generally with that of Figures 9 and 10, except that the key slot 8^g is formed in the housing 2^g rather than in the plunger or central friction member 21^g. This necessitates moving the wedges 18^g and associated curved plate springs 17^g toward the follower portion 49^g of the central wedge member 21^g, making it necessary to use shorter release springs 40^g. Although the gear is shown single-ended, it will be understood that it may be converted into a double-ended gear by making the parts to the right of the transverse central plane 56^g correspond with those shown at the left of said plane in Figure 15. It will also be understood that although four release springs are illustrated, I do not wish to be limited to this number, as two placed diagonally, or some other arrangement, may be employed, if desired. It will also be understood that lead inserts 32^g may be employed in some, or all, of the friction surfaces in this or other embodiments of my invention.

The use and operation of the gears previously described, if double-ended, may be as described for gears of the embodiment of Figures 1 and 2. If single-ended, the gear may be used as a conventional friction draft gear, as will be understood, except that where a portion thereof is slotted to receive a draft key, the gear may be used to replace a conventional friction draft gear and an associated slotted front follower.

From the foregoing description taken in connection with the accompanying drawings, it will be seen that I have devised an improved form of series draft gear or cushioning mechanism enclosed in a housing as a unitary cushioning device and adapted for use to provide differential absorbing action under buff and draft or so that the total capacity of the gear need not be used under both buff and draft. The friction energy absorbing capacity is not only provided by the engagement between the friction surfaces on the double wedge and associated friction shoes or elements, but also by engagement of the friction shoes on the adjacent partition, and some or all of said friction surfaces are desirably provided with lead inserts 32 or other means for preventing sticking and providing smooth action for the gear. The angularity of the inclined friction surfaces is such that release of the gear is effected by the curved plate springs without the necessity of the separate releasing springs, except where such are used.

Although I have illustrated certain preferred embodiments, it will be understood that I do not wish to be limited to the exact forms disclosed as modifications may be made within the spirit and scope of the appended claims without departing from the broad aspect of my invention. Although the main frictional resistance is generated by the engagement of the inclined friction surfaces on the double wedges and associated friction elements, it will be understood that the inner ends of said friction elements preferably provide friction surfaces normally in engagement with the transverse walls of the housing, thereby augmenting the frictional capacity of the mechanism.

I claim:

1. Cushioning mechanism comprising a housing slotted for receiving a positioning draft key,

friction blocks movable laterally therein, a wedge block disposed between said friction blocks, resilient means disposed between said friction blocks and the adjacent sides of said housing, and means interlocking said wedge block and friction blocks together.

2. Cushioning mechanism comprising a housing with intermediate partition means and pockets at each end, friction blocks movable outwardly in said pockets upon compression of the mechanism, a wedge block disposed between said friction blocks in each pocket, said friction blocks and wedge block being formed with cooperating shouldered portions for limiting relative movement therebetween, and resilient means disposed between said friction blocks and the adjacent side walls of said housing.

3. In railway draft rigging, in combination with draft sills, cushioning mechanism comprising a housing mounted for longitudinal movement between said sills, said housing comprising side walls and a transverse wall, intermediate the ends thereof, connecting said side walls, said housing being formed with a pocket adjacent an end thereof, friction blocks movable laterally in said pocket in frictional engagement with said intermediate wall, a wedge block disposed between said friction blocks for urging them apart, upon compression of the mechanism, with its outer end disposed beyond said pocket, and formed with an outer face for receiving buffing forces, means limiting outward movement of said wedge block with respect to said housing, and resilient means disposed between and in engagement with said friction blocks and the side walls of said housing.

4. Cushioning mechanism comprising a housing defined by walls and constructed for movable mounting with respect to a railway vehicle, said housing having a pocket at an end, friction blocks movable laterally in said pocket, a central wedge between the friction blocks in said pocket, curved plate springs disposed between said friction blocks and the adjacent walls of said housing, a bolt and associated nut for holding said central wedge assembled with the housing, a washer formed of material which readily disintegrates when the mechanism is in service, associated therewith for making the mechanism slightly shorter initially, and a combined socket wrench and retainer member for said nut.

5. Cushioning mechanism comprising a housing, friction blocks laterally movable therein, a follower, an associated wedge block portion fitting between said friction blocks, resilient means disposed between said friction blocks and the adjacent walls of the housing, and lugs extending from the ends of longitudinal walls of said housing and fitting over the adjacent edges of the follower portion for limiting outward movement thereof.

6. Cushioning mechanism comprising a housing, friction blocks movable laterally therein, a follower with an integral double wedge member fitting between said friction blocks, said member being slotted, a key passing through said slot and slots in the corresponding walls of the housing for limiting movement between said wedge and housing, and resilient means disposed between said friction blocks and housing.

7. Cushioning mechanism comprising a housing, friction blocks movable laterally therein, a follower, an associated wedge block portion fitting between said friction blocks, resilient means disposed between said friction blocks and the ad-

jacent side walls of the housing, and means extending from the side walls of said housing and fitting over the adjacent edges of the follower portion for limiting movement thereof.

5 8. Cushioning mechanism comprising a housing, friction blocks movable laterally therein, a follower with an integral double wedge member fitting between said friction blocks, means for limiting outward movement of said wedge member with respect to said friction blocks, inward movement of said wedge member being limited by engagement between said follower and housing, and resilient means disposed between said friction blocks and the corresponding side walls

10 10 member with respect to said friction blocks, inward movement of said wedge member being limited by engagement between said follower and housing, and resilient means disposed between said friction blocks and the corresponding side walls 15 of the housing.

15 9. Cushioning mechanism comprising a housing with a pocket considerably shorter than the housing and defined by longitudinal and other walls, friction blocks tapering one way only from end to end and movable laterally in said pocket, a member with a tapered wedge portion fitting between said friction blocks, resilient means disposed between each friction block and an adjacent longitudinal wall, release spring means 20 acting on said member and disposed between said friction blocks, and means for limiting movement of said member away from said housing.

25 10. Cushioning mechanism comprising a housing member with a pocket defined by longitudinal and other walls, friction blocks movable laterally in said pocket, a wedge member with a tapered portion fitting between said friction blocks, resilient means urging said blocks into engagement with said tapered portion, an auxiliary friction member engaging transverse friction surfaces on said friction blocks, and a release spring urging said auxiliary member from said wedge member and into engagement with said friction blocks.

30 11. Cushioning mechanism comprising a housing with a pocket defined by longitudinal and transverse walls, friction blocks movable laterally in said pocket, a member with a tapered portion fitting between said friction blocks, resilient

means housed in said pocket and disposed between each friction block and an adjacent longitudinal wall, release spring means housed partially in said housing and partially in said member and acting between transverse wall portions of said member and transverse wall portions of said housing, intermediate the ends of said mechanism and means for limiting movement of said member away from said housing.

35 12. Cushioning mechanism including housing means, longitudinally movable between associated sills, comprising side walls, pockets in said housing means defined by said side walls and webs extending inwardly therefrom, said webs defining an access opening in said housing, friction wedges movable laterally in said housing means, wedging means fitting between said friction wedges and adapted to be actuated by an associated coupler stem, resilient means disposed in said pockets and acting on said side walls, said resilient means being stressed by lateral movement of said friction wedges upon longitudinal movement of said wedging means therebetween, and means for limiting movement of said wedging means out of said housing means, said friction wedges and resilient means adapted to be inserted into said housing through said access opening.

40 13. Cushioning mechanism including housing means, longitudinally movable between associated sills, comprising side walls, pockets in said housing means defined by said side walls and webs extending inwardly therefrom, friction wedges movable laterally in said housing means, wedging means fitting between said friction wedges, guided by adjacent portions of said webs, and adapted to be immediately actuated by an associated coupler, and resilient means disposed in said pockets and acting on said side walls, said resilient means being stressed by lateral movement of said friction wedges upon longitudinal movement of said wedging means therebetween.

DONALD S. BARROWS.
